UNITED STATES PATENT OFFICE

WALTER J. HAUSMAN, OF UPPER DARBY, PENNSYLVANIA, ASSIGNOR TO UNDERWOOD
ELLIOTT FISHER COMPANY, OF NEW YORK, N. Y., A CORPORATION OF DELAWARE

TYPEWRITING MACHINE

Application filed December 15, 1924, Serial No. 755,915. Renewed September 19, 1938.

This invention relates to typewriting machines of that class employing collating mechanism of the general character disclosed in the patent to J. A. B. Smith, No. 1,503,069, granted July 29, 1924.

It has been proposed to mount auxiliary ribbons permanently in the typewriting machine for use between the work-sheets for manifolding purposes, but this is found to be impracticable except for a work-sheet which is inserted in the machine only once for the typing of the entire sheet. One of the objects of the present invention is to make it practicable to employ auxiliary interposed 15 ribbons in cases where it is necessary to reinsert the sheet into the machine every time that an item is to be typed thereon. In some kinds of bookkeeping or statement work, a sheet must be reinserted many times before 20 it is filled up, as only one item is typed at each insertion. In attempting to employ the usual auxiliary ribbon for this purpose, it is found that the sheets become so crooked from contact with the auxiliary ribbon, by 25 reason of the frequent insertions, as to prohibit the use of such ribbon. Moreover, the difficulty of inserting a sheet between the platen and the auxiliary ribbon, which extends along the entire front of the platen and close 30 thereto, is difficult and time-consuming.

One of the objects of the present invention therefore is to overcome this difficulty and to afford to the operator the use of an interposed ribbon without incurring the aforesaid objections. To this end it has been contrived that no ribbon is mounted in the machine, and therefore cannot interfere with the manipulation of the sheets or crook the same. The sheets are quickly placed in the 40 machine and collated at desired positions for the manifolding of a single-line entry; and after the sheets have been so collated, an ink-ribbon is dropped in between the sheets. The ribbon, for this purpose, is mounted upon a 45 large card or thin stiff frame, which readily slips edgewise into position between the work-sheets. In order that the inserted ribbon shall be readily located at the printing line, there is provided upon the card a locating shoulder or edge, which engages with a

corresponding locating shoulder or edge that is provided upon the typewriting machine, so that it is only necessary to drop in the card far enough for it to engage with the locating shoulders on the typewriting machine, whereupon the item may be typed. Upon completing the typing of the item, the card may be withdrawn, and the work-sheets may also be withdrawn, and new sheets inserted and collated, whereupon the same card 55 may be inserted between the new sheets; and so on. The work thus proceeds with celerity, and the advantage is preserved of making an ink-ribbon copy as distinguished from the objectionable carbon-copy. 60

Another feature is that the inserted ribbon may be of the bichrome variety, and may therefore make a copy of the same color as the original typing upon the outside sheet; the inserted ribbon being adjustable or shift- 65 able from one printing field to the other, or locatable in either printing field at will. 70

For collating the sheets, there is provided a device which clamps each sheet upon a separate slide; each slide with its sheet being 75 adjustable as a unit independently of the other slide and sheet; and this feature of the invention may be employed for other purposes, in machines in which carbons are used in place of auxiliary ink-ribbons for 80 manifolding.

In machines of this character it is desirable to manifold collated work-sheets, as, for example, a ledger-sheet and a monthly statement-sheet. These two are usually fed 85 around the platen from the rear, up across the front of the platen to a collating table, where an edge of each sheet is aligned vertically and the last printed entry thereon aligned to the wing-scales at the front of the platen. To 90 align these two work-sheets simultaneously with a carbon-inlay and preserve uniformly-spaced successive records was a painstaking operation and required skill to preserve neat, uniformly-spaced-off records for singly-in- 95 serted items.

One feature of the present invention provides that the under or statement sheet may be adjusted under the platen from the rear, brought up over the face of the platen and 100

carried to the collating table or plane, where one edge is aligned accurately to a side gage and the last typed entry adjusted approximately to the printing line on the platen, 5 and the sheet then clamped to the face of a slide mounted upon the table for an up and down sliding movement. The second or ledger sheet may be similarly adjusted around the platen outside the statement-sheet and adjusted accurately to a second side gage, and 10 the last line typed thereon also approximately adjusted to the printing position regardless of the adjusted position of the previously-adjusted statement-sheet clamped to the first slide on the collating table. Each slide on 15 the collating table may be moved up or down by a rack-and-pinion connection operated by a finger-wheel at each side of the collating table. By turning these two finger-wheels the ledger and statement sheets clamped to the two slides may be accurately adjusted to the front scale and in register with each other, and, when so adjusted, the released feed-rolls 20 may be restored to hold the two sheets in adjusted relation against the platen. The clamps on both slides are now raised to release the two sheets, and the platen line-spaced for the new entry to be entered on the work-sheet. By adjusting each sheet separately to a sheet- 25 edge gage, and then clamping the sheet to a slide, prevents any shifting of the first-adjusted sheet during the adjustment of a second superposed sheet, and this not only permits more accurate registry between entries, but 30 reduces the time required in changing the work-sheets.

The two-color typing is done on the outer work-sheet through the use of the usual bichrome ribbon vibrated across the printing 40 point of the types, and also provides for two-color manifolding for the under work-sheet through the introduction of an auxiliary bichrome ribbon-section between the two work-sheets that are shiftable between stop positions to bring either field of the ribbon into 45 a positive registry with the printing point, and thus reproduce the outer sheet with the two-color effect.

The auxiliary bichrome ribbon-section is 50 mounted upon a carrier, in such a manner that it can be inserted between two work-sheets to cover the printing position, and be locked at one of two fixed positions to bring either inked section to the printing zone at will, and 55 thus manifold in two colors, or may be removed at will when it is desired to type the outer sheet without manifolding.

Other features and advantages will herein-after appear.

60 In the accompanying drawings,

Figure 1 is a front elevation of the platen, bichrome ribbon-mechanism, collating table and work-sheet slides adjusted thereto in operative relation to the platen of an Underwood typewriting machine.

Figure 2 is a cross-section through the collating table on a plane indicated by the line 2-2 of Figure 1.

Figure 3 is a vertical section through the collating table on a plane indicated by the 70 line 3-3 of Figure 1.

Figure 4 is a vertical section through the collating table, illustrating in detail the auxiliary ribbon holding and suspending means.

Figure 5 is an enlarged view of the lower 75 end of Figure 4, taken approximately at the line 5-5 of Figure 6.

Figure 6 is a front elevation with the work-sheets removed, the paper-clamps shifted to inoperative position, and the auxiliary ribbon 80 and its carrier positioned in operative relation to the printing point of the platen.

Figure 7 is a rear elevation of Figure 6 85 stripped of everything but the auxiliary ribbon-controlling device.

Figure 8 is a rear elevation of the two collating tables detached from the machine with the work-sheet slides mounted thereon in operative position.

Figure 9 is a detail view, in section, of one 90 of the work-sheet clamps.

The platen 10 of an Underwood standard typewriting machine, against which the type-bars 11 strike upon the front side, is supported by a platen-shaft 12 having bearings in the end plates 13 joined together by a tie-rod 14 and a paper-table 15 forming a platen-frame shiftable up or down between two stop positions within the usual Underwood traveling carriage (not shown). The platen 10 has two feed-rollers 16 that may be cast off in the usual Underwood manner as disclosed in the patent to H. S. McCormack, No. 819,785, dated May 8, 1906.

The paper-table 15 curves under the platen to a point just below the printing position, and forms a deflector or open passageway between said table and the face of the platen.

The machine is also equipped with two front collating table supports or sections 17 and 18. These are supported upon cross-bar 19 and are capable of adjustment for different widths of work-sheets, or to different positions longitudinally of the platen. The cross-bar 19 may be secured at each end to brackets 20 mounted upon rods 14, 21, 22, and supported by the end plates 13 and brackets 23. Upon the front face of these two sections 17 and 18, table slides 24 and 25 are mounted for independent up and down movements over the stationary support. This up and down movement is promoted by three tongues 26, 27 and 28 secured to the under face of each slide to engage with and pass through three slots 29, 30 and 31 in each section 17 and 18. To prevent said slides from falling outwardly, the two tongues 26 and 28 are provided with plates 32 that span the slots 29 and 31 and bear against the rear face of the tables. This construction provides for 120 125 130

a free up and down movement for the slides, and to control this movement the center tongue 27 of each slide projects beyond the rear face of the collating tables and is provided with cross-cut rack-teeth 33, Figure 3. These teeth are in mesh with a pinion 34 fixed to the inner end of a shaft 35 that takes bearings within the ears of a bracket 36, Figure 2, secured to the rear face of the collating tables with the free ends of each shaft provided with a finger-wheel 37.

The plane of the collating-table-sections 17 and 18 and the slides 24 and 25 is nearly perpendicular, and hence the slides will drop to the lowest position determined by the engagement of the lower ends of the tongues 27 striking the ends of the slots 30, and this lack of control over the position of the slides, at all times would defeat one object of the invention, namely, to adjust the slides and hold them in any adjusted position. To these ends each shaft 35 has an adjustable braking means comprising a compression-spring 38, Figure 8, coiled about the shaft and confined 23 between an ear 36^a of the bracket 36 and a collar 39 upon the shaft that prevents endwise movement of the shaft from the action of this spring 38. A second collar 40 is adjusted against the opposite face of the ear 36^a, which provides sufficient drag against the rotation of the shaft 35 to offset the action of gravity on the slide 24 or 25.

Viewing the front of the machine, as in Figure 1, the right-hand edge of the slide 24 and the left-hand edge of the slide 25 are bent forwardly at right angles to form long gaging faces 41 and 42. As shown in this figure, the outer work-sheet A, which may be described as a ledger-sheet, is adjusted to the side gage 42, and the innermost sheet B, which may be a statement-sheet, adjusted to the gage 41, and the relative adjusted positions of these two gaging faces are such that there is a narrow strip along the side edges, as indicated at X, where the two work-sheets do not overlap each other, and, within this single-ply work-sheet space, a clamping means is established to bind each sheet to its respective slide 24 or 25. This clamping means, Figures 50 1 and 9, comprises two arms 43 joined together by a rubber-coated bar to form a long pressure pad 44 adapted to swing, as a unit, upon a rod 45 suspended at each end from the ears of a bracket 46 secured to the outer 55 face of each side gage 41 and 42 and spring-pressed by one or two two-way springs 47, arranged to hold the pad 44 in a raised inoperative position, or to press the pad against the face of its slide at another position. The 60 longitudinal edge of the work-sheet B engaging the long gage face 41 of the slide 24 and the long spring-pressed pad 44 pressing the work-sheet against the face of the slide, provide an effective gripping means to control the movement of the work-sheet during

the movement of the slides for purposes presently to appear. The clamp is mounted to engage the sheet at the side, and is open at the top to permit the sheet to extend up past the clamp.

The outer work-sheet A is typed through the usual bichrome ribbon 48, fed longitudinally through the usual ribbon-carrier 49, that is vibrated to cover and uncover the printing position by a ribbon-vibrating lever 50 operated by a universal bar 51 at each type action. The two longitudinal fields of the bichrome ribbon are brought to the printing position, at will, in the well-known Underwood manner, by two-color-ribbon-shift mechanism, comprising an actuator 52 having two slotted ears 53 to engage with two wrist-pins 54 and 55 on the lever 50. The actuator 52 is settable by a crank-arm 56 secured to a rock-shaft 57 operated by the usual ribbon-shift keys 58 and 59 over the keyboard. Further details regarding this ribbon-shifting mechanism is disclosed in the patent to J. C. McLaughlin, No. 1,066,029, granted July 1, 1913.

In the present invention a section of similar bichrome ribbon, used on the ledger-sheet, is introduced between the two work-sheets and controlled by a manually-shiftable ribbon-carrier, so that exact duplicate records may be made on each work-sheet in both typing and color effect. To this end each collating-table-section 17 and 18 at the upper right and left hand corners respectively are formed with extensions, Figures 3 and 8, that project outwardly from the tables a short distance, then are bent forwardly at right angles and again bent at right angles away from the center of the machine; these several bends in these extensions result in an ear 60 at the upper corner of each collating table that is parallel to the face of the tables and are employed to support a bar or strip 61, extending across the collating tables. This bar 61 may be removably secured to the face of the ears 60 by spring-detent-clips 62 secured to said ears and formed with V-shaped terminals 63 to overlie the bar and interlock within slots 64 formed at each end of the bar 61 and to engage the upper edges 65 of said bar for locking the bar in one of two positions. In its lowermost position the bar 61 is arrested against stop 60^a bent up from the ears 60. The bar 61 supports a cardboard-section 66 that is co-extensive with the width of the collating tables between the two side gages 41 and 42 and extends downwardly to the position adjacent the lower edges of said tables. This cardboard-section may be a thin sheet of hard, wiry grade of fiber-board and may be permanently secured at the upper edge to the bar 61, as by rivets. The lower end of this cardboard-section 66 has three metal fingers 67 permanently secured to the front face thereof, with one finger at the center and one near each side edge

of the cardboard. These fingers 67 project below the edge of the cardboard and are arranged to support a long inverted U-shaped metal clip 68, Figure 5, secured to the faces of these three fingers, in any suitable manner, 5 with one wall of the clip embossed to form raised-up ridges 69 within the clip to separate the two walls thereof, and thus provide an open longitudinal gap at the open end of the clip. This clip 68 may be formed from thin 10 resilient metal, so that the wall not secured to the fingers may bear against the faces of the ridges 69 under tension. The clip 68 is arranged to support an auxiliary ribbon-carrier 15 comprising a stiff paper-tongue 70 that may be forced within the opening between the two walls of the clip 68 by riding over the ridges 69 and flexing the opposite wall of the clip, in such a manner that an effective grip on 20 the paper is maintained. The paper-tongue 70 extends downwardly from the clip 68 to a position below the printing line on the platen and is provided with a long rectangular slot or opening 71 aligned to the printing position 25 of the platen. This slot is covered over on the front side by a bichrome ribbon-section 72, and the width of the slot may be approximately the same width as the ribbon, but the ribbon may be slightly longer than the length 30 of the slot to provide that each end of the ribbon may be permanently pasted to the paper-tongue 70 and effectively cover the whole area of the slot.

As shown at Figure 6, which is a front elevation, the lower field of the bichrome ribbon 72 is at the printing line across the platen. To change this ribbon-field the projecting ends of the bar 61 may be gripped by the operator and the bar forced downwardly 40 against the stops 60 and until the detent 62 interlocks with the edge 65 of said bar which lowers the ribbon-section 72 and moves the ribbon-section 72^a to the printing position. Hence the up and down adjustment of the 45 bar 61 to one of the two detent positions changes the operative longitudinal ribbon-fields relatively to the printing line and provides that ribbon-inked manifold may be produced in a uniform color, or selectively 50 in varying colors in the same line, at will.

As previously described, the ribbon-section 72 is permanently secured at its ends to the front faces of the paper-tongue 70. As the ribbon-tongue must be introduced between 55 the two work-sheets, it is obvious that the front exposed face of the ribbon will be brought into contact with the rear face of the front work-sheet A, and typed impressions will not only be transferred to the back 60 of this sheet, but the exposed ribbon will cause more or less crocking; both features indicating a waste of ink from the very limited supply carried by the short ribbon-section. To conserve the limited supply of ink available in so small a ribbon-area, a cover of thin

paper 73 may be pasted to the paper-tongue 70 to cover the whole ribbon-section, which not only prevents smearing the adjacent face of the work-sheet, but prolongs the life of the ribbon.

From this description it will be seen that the auxiliary ribbon-carrier, comprising the two paper-elements 70 and 73, may be assembled for various lengths of work-sheets and for various colors in the bichrome fields; that the carrier as a unit may be instantly removed from the clips and replaced by another carrier having different colored ribbon-fields, and, while the invention has been shown and described for a bichrome ribbon, it will be understood that an auxiliary ribbon of a single color may be employed when the bichrome features are not desired.

From this description the operation will be readily understood to be as follows: The two slides 24 and 25 are adjusted to a central position on the collating tables; the bar 61 and its attached parts are removed as a unit; the two pads 44 are raised to inoperative positions, shown at Figure 6, and paper-feed-rollers 16 are released to the inoperative positions, shown in Figure 3. The first sheet to be adjusted is the sheet next to the platen-face which will be called a statement-sheet B. This sheet is forced under and around the platen from the rear, and guided by the deflector 15 and the usual wing-scales 74 at the front of the platen to the collating table.

If previous entries have been made on this sheet, the sheet is drawn upwardly from the front until the last printed line is above the edge of the scales 74, and, without accurately aligning this printed line to the scales, the right-hand edge of the sheet is aligned to the gage 41 of the slide 24, and the pad 44 attached to the side edge of the slide is snapped down to press the sheet firmly against the face of the slide underneath, as shown in Figure 1. A second work-sheet A, which may be a ledger-sheet, is forced around the platen and around the adjusted sheet B until the leading edge of the sheet is brought up over the collating tables where the last typed entry thereon is approximately aligned to the scales 74, and the left hand edge accurately aligned to the gage 42 and the associated pad 44 snapped down to bind this sheet to the face of the slide 25.

The adjustment of these two separate work-sheets as described allows the operator the use of both hands to quickly and accurately adjust each sheet separately to a side gage, and, when both sheets have been adjusted and clamped with slides, the operator employs both hands to turn the two finger-wheels 37 which move the slides 24 and 25 up and down to adjust the last typed entry on its work-sheet to the edges of the scales 74, and, when so adjusted, the feed-rollers 16 are restored to press both work-sheets A

and B against the face of the platen, the two pads 44 are raised to release the work-sheets from the slides, and the platen and both work-sheets may be line-spaced for the new entry to be typed. The outer sheet A is drawn forwardly to bend over the edges of the scales 74, as shown in dotted lines in Figure 5, and the bar 61 is adjusted to the ears 60 after first inserting the auxiliary ribbon-carrier between the two work-sheets. The detents 62 interlocking with the slots 64 will hold the auxiliary ribbon in a fixed longitudinal position relative to the printing line. As the usual entries on the outer sheet A are made through the upper or black section of the ribbon, the auxiliary ribbon will also be adjusted to bring the upper or black field of the ribbon to the printing position through the interlocking of the detents 62 with the edges 65 at each end of the bar 61. These several adjustments having been completed, the usual center roller 76 is swung toward the platen to bear against the outer face of the sheet A to take up any sag in the work-sheets and still leave the sheets loosely positioned to enable subsequent line-spacing movements to be made without disturbing the position of the auxiliary ribbon-carrier. The impact of the type against the usual vibrating ribbon 48 transfers inked characters to the ledger-sheet A and manifolds these characters through the auxiliary ribbon to the statement-sheet B in the same color. And should occasion arise to enter a debit transaction on the ledger-sheet in a distinguishable color, the usual bichrome ribbon-shift-keys 58 and 59 of the Underwood machine provide that the lower field of the ribbon may be vibrated to the printing position, and, by lifting the bar 61, the slots 64 will interlock with the detent-springs 62 and the lower section of the auxiliary ribbon will be moved to cover the printing zone of the types, as at Figure 6, and the debit transactions entered on the ledger-sheet through the red section of the standard ribbon 48 will be manifolded to a statement in a similar color.

As the outer sheet A nearly covers the entire face of the sheet B, at the end of the last typing operation on the sheets and before the sheets are removed, a pencil-mark indicated at 77, Figure 1, may be drawn on sheet B adjacent the right-hand edge of the sheet A, indicating the last line position on the sheet to assist in readjusting the sheet B when it is adjusted to the printing position for subsequent entries. This mark 77 is essential because the typed matter on the under sheet B is covered by the outer sheet A.

The typewritten entries on the two work-sheets having been completed, the center roller 76 is swung out of the way, the bar 61 is removed from the ears 60 to withdraw the auxiliary ribbon from between the two work-sheets, and the two feed-rollers 16 are thrown

to inoperative position. Figure 8, and the two work-sheets removed by drawing them upwardly from around the platen.

While the machine has been described as being adapted for typing a ledger-sheet and manifolding a statement-sheet, it will be understood that other forms of work-sheets may be employed. One primary factor of the invention resides in the manner of inserting an auxiliary bichrome ribbon, at will, between the two superposed work-sheets and providing shifting means for this auxiliary ribbon so as to enable the operator to manifold the under sheet in exactly the same form and characteristics as typed on the outer sheet.

It will also be noted that in providing means whereby this auxiliary ribbon may be detached from the collating tables, the collating features associated with the tables and guides may be employed for manifold work where it is more advantageous to insert carbon-inlays between two work-sheets before they are adjusted around the platen, the pads 44 being raised to inoperative positions.

It will also be understood that in some forms of work-sheets employing ruled lines, these ruled lines may vary with the two work-sheets and require individual adjustments of the sheets without employing the usual line-spacing device. This may be readily accomplished by line-spacing each sheet independently to the printing position by turning the finger-wheels 37 to draw their work-sheet around the platen distances that vary with the spacing of the ruled lines of the two work-sheets.

In some forms of superposed work-sheets, it may be advantageous at intervals to silence the vibrating ribbon to enable typed entries to be manifolded on the undersheet without making any record on the outer sheet. To this end, the usual Underwood ribbon-shifting mechanism includes a shift-lever 78 that operates to rock the shaft 57 and move the actuator 52 to an inoperative position relative to the two wrist-pins 54 and 55, and the ribbon 48 will remain inactive below the field of the types, in a manner disclosed in the patent to J. C. McLaughlin, No. 1,211,203, granted January 2, 1917. By raising the bar 61 to rest upon the flaring ends of the spring 62, the auxiliary ribbon may be rendered temporarily inoperative, when records are made on the outer sheet only.

Variations may be resorted to within the scope of the invention, and portions of the improvements may be used without others.

Having thus described my invention, I claim:

1. In a typewriting machine having a platen, upon which superposed work-sheets may be adjusted to the printing position and held for a single line typing operation, and also having a platen-frame and printing in-

- strumentalities, the combination of a de-
5 mountable bicolor ribbon-carrying card or
frame for manifolding, said frame introduc-
ible as a unit between the previously-adjusted
stationary work-sheets, and card-supporting
and ribbon-locating means on the platen-
frame variably engageable with the card
10 after its insertion between the work-sheets
according to the ribbon-field presented to the
printing line.
2. In a typewriting machine having a
platen, upon which superposed work-sheets
may be adjusted to the printing position and
held for a single line typing operation, and
15 also having a platen-frame and printing in-
strumentalities, the combination of a de-
mountable bicolor ribbon-carrying card or
frame for manifolding, said frame introduc-
20ible as a unit between the previously-adjusted
stationary work-sheets, and card-supporting
and ribbon-locating means on the platen-
frame variably engageable with the card
25 after its insertion between the work-sheets,
said supporting and locating means in-
cluding a detent fastened upon the frame and
co-operative with means shiftable with the
ribbon-card to register and hold either rib-
30 bon-field at the printing line and between the
work-sheets.
3. In a typewriting machine, the combina-
tion with a platen upon which work-sheets
may be superposed and adjusted to the print-
ing position and a platen-frame, of printing
instrumentalities, a demountable ribbon card
35 or frame insertible as a unit between pre-
viously-adjusted work-sheets to manifold
the typed matter, and supporting and locat-
ing means upon the platen-frame engageable
40 by the card when inserted, including means
upon the platen-frame detachably interlock-
ing with corresponding means upon the card,
for locating the ribbon at the printing line.
4. In a typewriting machine, the combina-
tion with a platen, of printing instrumental-
ities, a collating table at the delivery side of
45 the platen upon which work-sheets may be
superposed for alignment to the printing
position, inking means insertible between the
sheets after collation thereof and removably
50 secured to the collating table between the
work-sheets for manifolding purposes, and
means to releasably detain said inking means.
5. In a typewriting machine, the combina-
tion with a platen, of printing instrumental-
55 ties, a collating table at the delivery side of
the platen upon which work-sheets may be
superposed for alignment to the printing
position, inking means removably secured to
the collating table between the work-sheets,
60 including a ribbon-section adapted to the
width of the work-sheets, and a card or thin
frame insertible between the sheets.
6. In a typewriting machine, the combina-
tion with a platen, of printing instrumental-
65 ties, a collating table at the delivery side of
the platen upon which work-sheets may be
superposed for alignment to the printing
position, inking means removably secured to
the collating table to retain said inking means.
7. In a typewriting machine, the combina-
tion with a platen, of printing instrumental-
70 ties, a collating table upon which work-sheets
may be superposed for alignment to the print-
ing position, and inking means removably
secured to the collating table and adjustable
75 between the work-sheets to manifold in vary-
ing colors.
8. In a typewriting machine, the combina-
tion with a platen, of printing instrumental-
80 ties, a collating table upon which work-sheets
may be superposed in alignment to the print-
ing position, inking means in the form of an
insertible card or frame removably secured
85 to the collating table between the work-sheets,
and means to retain said card or frame.
9. In a typewriting machine, the combina-
tion with a platen upon which work-sheets
may be superposed and adjusted to the print-
ing position, of an adjustable stationary bi-
90 chrome ribbon-section occupying a position be-
95tween the work-sheets to manifold typed mat-
ter in either color, and means to support said
ribbon-section removably in different selected
widthwise positions.
10. In a typewriting machine, the combina-
tion with a platen upon which work-sheets
100 may be superposed and adjusted to the print-
ing position, of a vibratory front ribbon hav-
ing inking fields of different characteristics
105 to print upon one work-sheet, and an ad-
justable stationary ribbon occupying a posi-
tion between the pre-adjusted work-sheets
having the same characteristics as the first-
named ribbon to manifold typed matter in
110 identical colors.
11. In a typewriting machine, the combina-
tion with a platen upon which work-sheets
115 may be superposed and adjusted to the print-
ing position, of printing instrumentalities, a
vibratory bichrome ribbon, a detachable
manifolding bichrome ribbon inserted be-
120tween the work-sheets, and means to remov-
ably support in different positions the inserted
ribbon to bring into use different fields there-
of.
12. In a typewriting machine, the combina-
tion with a platen around which a pair of
work-sheets may be adjusted and superposed,
125 of printing instrumentalities including an
inking ribbon, a collating table at the delivery
side of the platen, a slide comprising a gage
and a clamp to align each work-sheet to the
printing line on the platen, and inking means
removably secured to the collating table to
occupy a position between the two adjusted
sheets for manifolding purposes.

13. In a typewriting machine, the combination with a platen around which a pair of work-sheets may be adjusted and superposed, of printing instrumentalities including a bi-chrome inking ribbon, a collating table at the delivery side of the platen, a slide comprising a gage and a clamp to align each work-sheet to the printing line on the platen, bi-chrome inking means, and means at the collating table to removably support said inking means selectively in either of two positions between the adjusted work-sheets, for mani-folding in identical colors. 70
14. In a typewriting machine, the combination with a platen around which a work-sheet may be adjusted, of a collating table on a delivery side of the platen to receive superposed work-sheets, and movable means mounted upon the collating table to adjust the work-sheets independently of each other to the printing line of the platen. 75
15. In a typewriting machine, the combination with a platen around which a work-sheet may be adjusted, of a stationary collating ta-ble on the delivery side of the platen to re-cieve the work-sheet, a sheet carrier having a sheet gage and slidably mounted upon the collating table to adjust the sheet bodily to the printing line of the platen, and releasable 80 means to hold another sheet stationary at the operation of adjusting the first work-sheet. 85
16. In a typewriting machine, the combination with a platen around which a pair of superposed work-sheets may be adjusted, of a collating table on the delivery side of the platen to receive the work-sheets, and a set of movable sheet-carriers mounted upon the collating table to clasp and adjust each sheet in-dependently of the other to the printing line, 90 each of said sheet-adjusters movable with its sheet independently of the others. 95
17. In a typewriting machine, the combination of a platen around which a pair of superposed work-sheets may be adjusted, a collating table on the delivery side of the platen to receive the work-sheets, and slides mounted upon the collating table to indi-vidually adjust each work-sheet to the print-ing line. 100
18. In a typewriting machine, the combination with a platen around which a pair of superposed work-sheets may be adjusted, of a collating table on the delivery side of the platen to receive the work-sheets, a slide 105 mounted upon the collating table for each work-sheet, comprising a gage and a clamp, and means for individually operating each slide to adjust the work-sheets to the print-ing position. 110
19. In a typewriting machine, the combination with a platen around which a work-sheet may be adjusted, of collating slides mounted at the delivery side of the platen, clamps to bind the work-sheets to the slides, 115 and means to move either slide in either di-rection, independently of the other slide, comprising a rack on each slide, and pinions for the racks. 120
20. In a typewriting machine, the combination with a platen around which a work-sheet may be adjusted, of collating slides mounted at the delivery side of the platen, means for mechanically gaging and clamping sheets separately to the slides, and means for manually operating the slides independently of each other to afford fine adjustment of the work-sheets relatively to the printing line. 125
21. In a typewriting machine, the combination with a platen around which a pair of work-sheets may be adjusted, of a collating 80 table at the delivery side of the platen and including independently moving slides, a side-edge work-sheet gage on each slide for truing the sheet relatively to the printing line, and means for clamping one work-sheet to each slide. 85
22. In a typewriting machine, the combination of a platen, a rear paper-table to guide superposed work-sheets around the platen, a collating table on the delivery side of the platen to receive the work-sheets, the collat-ing table including sheet-carriers having means for clamping the work-sheets and moving the clamped sheets bodily to different positions independently of each other, to in-dependently adjust the last entry on each work-sheet to the printing line, and line-spacing means to adjust both work-sheets in unison a line-space distance above the print-ing line. 90
23. In a typewriting machine, the combination with a platen and a sheet-collating device at the delivery side thereof, upon which sheets may be collated relatively to each other and to the printing line, of means to hold the collated sheets against the platen after their collation, and an inking device including a card or thin frame and an ink-ribbon carried thereby, said device being inser-tible as a unit between the collating sheets. 105
24. In a typewriting machine, the combination with a platen and a sheet-collating device at the delivery side thereof, upon which sheets may be collated relatively to each other and to the printing line, of means to hold the collated sheets against the platen after their collation, and an inking device including a card or thin frame and an ink-ribbon carried thereby, said device being inser-tible as a unit between the collating sheets, means being provided upon said col-lating device to engage said inking device to locate the same relatively to the printing line and detain it demountably in working position. 110
25. The combination with a revolute platen, of collating slides mounted at the de-livery side of the platen for independent ad-justment relatively to the printing line, means upon each slide for gaging and clamp- 120
- 125
- 130

- ing a work-sheet thereto, an inking device in the form of a thin card or frame having an ink-ribbon mounted thereon and forming a unit insertible bodily between the collated work-sheets, and means to hold the collated sheets to the platen, means being provided for demountably locating and detaining said insertible inking unit. 26. The combination with a revoluble platen, of collating slides mounted at the delivery side of the platen for independent adjustment relatively to the printing line, means upon each slide for gaging and clamping a work-sheet thereto, an inking device in the form of a thin card or frame having an ink-ribbon mounted thereon and forming a unit insertible bodily between the collated work-sheets, and means to hold the collated sheets to the platen, means being provided for demountably locating and detaining said insertible inking unit, said locating means including gages on the collating device and corresponding gages upon said insertible unit. 27. A demountable inking unit for insertion between work-sheets held in a typewriting machine, said unit including a body-card or thin frame-portion to extend along the typewriter platen, an ink-ribbon to extend along the platen, and an ink-ribbon bearing portion hinged to said body-portion, and hinge-line extending lengthwise of the platen, to facilitate passing the unit around the platen. 28. A demountable inking unit for insertion between work-sheets held in a typewriting machine, said unit including a body-card or thin frame-portion to extend along the typewriter platen, an ink-ribbon to extend along the platen, and an ink-ribbon bearing portion hinged to said body-portion, and detachable therefrom, the hinge-line extending lengthwise of the platen, to facilitate passing the unit around the platen. 29. A demountable inking unit for insertion between work-sheets held in a typewriting machine, said unit including a body-card or thin frame-portion, an ink-ribbon, and an ink-ribbon bearing portion hinged to said body-portion, said body-portion in the form of a card, and hinge tabs secured upon said card, and said ink-ribbon portion having hinge means engaging said hinge tabs and provided with an opening in which is mounted the inking ribbon. 30. A demountable inking unit for insertion between work-sheets previously adjusted to the platen in a typewriting machine, said unit including a body-card or thin frame-portion and an ink-ribbon, a ribbon having plural inking fields, said body-portion having self-locating means projecting from opposite ends thereof for interengaging with locating and detaining means upon the typewriting machine and selectively operative to present different fields of the ribbon to the typing line of the platen between the work-sheets. 31. In a typewriting machine, the combination with a platen, of collating slides at the delivery side of the platen, said slides having gages and clamps for the work-sheets, and mechanism for operating the slides relatively to each other to adjust the work-sheets to printing position. 32. A demountable inking unit for insertion between work-sheets previously adjusted to the platen of a typewriting machine, said unit including a thin frame-section having a longitudinal typing opening, a ribbon secured to the frame to cover said opening, and a shield covering the front face of the ribbon to prevent abrasion of the ribbon-faces when inserted between the work-sheets. 33. A demountable inking unit for insertion between work-sheets previously adjusted to the platen of a typewriting machine, said unit including a thin frame-section having a longitudinal typing opening, a ribbon secured to the frame to cover said opening, and a shield covering the front face of the ribbon to prevent offsetting of typed characters upon the back of the foremost work-sheet. 34. In a front-strike typewriting machine, the combination with a platen, of a work-carrier arranged above the platen, means to support and guide said carrier upwardly and rearwardly, a releasable work-clamp upon said carrier, said clamp open at the top to permit the body of the sheet to extend up past the clamp, means to prevent said carrier from dropping, a line-feeding device, and means including a finger-piece to raise and lower said carrier independently of said line-feeding device, to adjust the sheet preparatory to the line-feeding operation. 35. In a front-strike typewriting machine, the combination with a platen, of a work-carrier arranged above the platen, means to support and guide said carrier upwardly and rearwardly, a releasable work-clamp upon said carrier, said clamp open at the top to permit the body of the sheet to extend up past the clamp, means to prevent said carrier from dropping, a rack-and-pinion mechanism to control the upward movement of the work-carrier, a line-feeding device for the work, and a finger-piece by which the up-and-down work-sweeping movements of the carrier are controllable, the work being swept around the platen by said finger-piece and carrier independently of said line-feeding device, to adjust the work to the printing line preparatory to the line-feeding operation. 36. In a front-strike typewriting machine, the combination with a platen, of a work-carrier arranged above the platen, means to prevent said work-carrier from dropping, fixed parallel guide-tracks extending upwardly and rearwardly, parallel guides upon said carrier and fitted to said guide- 100 105 110 115 120 125 130

tracks, a rack attached to said work-carrier and extending in the direction of said tracks, a pinion meshing with said rack for controlling the movement of the carrier, a work-clamp upon said carrier for engaging the body of the sheet and open to permit the sheet to extend above the carrier, a line-feeding device for the work, and a finger-piece by which the up-and-down work-sweeping movements of the carrier are controllable, the work being swept around the platen by said finger-piece and carrier independently of said line-feeding device, to adjust the work to the printing line preparatory to the line-feeding operation.

37. In a front-strike typewriting machine, the combination of a platen, a platen-frame, a frame mounted on said platen-frame, parallel tracks upon said frame and extending upwardly and rearwardly above the platen, a work-carrier wholly above the platen and having guides whereby it is mounted on said tracks, a releasable work-clamp upon said carrier, said clamp open at the top to permit the body of the sheet to extend up past the clamp, means to prevent said carrier from dropping, a line-feeding device, and a finger-piece operable independently of the line-feeding device and having means to raise and lower said carrier for sweeping the work around the platen for adjustment thereof preparatory to line-feeding the work.
